UNITED STATES PATENT OFFICE.

THOMAS SUMNER PATTERSON, OF ROSEMONT, PENNSYLVANIA, ASSIGNOR TO THE OIL AND WASTE SAVING MACHINE COMPANY, OF PHILADELPHIA, PENNSYLVANIA, A CORPORATION OF PENNSYLVANIA.

TURBINE-MOTOR.

No. 912,608.

Specification of Letters Patent.

Patented Feb. 16, 1909.

Application filed January 17, 1908. Serial No. 411,354.

To all whom it may concern:

Be it known that I, THOMAS S. PATTERSON, a subject of the King of Great Britain and Ireland, residing in Rosemont, Pennsylvania, have invented certain Improvements in Turbine-Motors, of which the following is a specification.

The object of my invention is to so construct a turbine motor that the motion of the driven shaft can be automatically reversed so that it will turn first in one direction and then in another.

My invention is particularly adapted for use in connection with washing machines used in laundry work, where it is required to drive the machine first in one direction a certain number of revolutions and then reverse it and drive it in the opposite direction a certain number of revolutions, but it will be understood that my invention may be used on other machines where it is desired to automatically reverse the movement of the driven shaft.

In the accompanying drawings: Figure 1, is a side view of sufficient of a washing machine with my improved motor attached, the motor being shown partly in section; Fig. 2, is a sectional view on the line 2—2, Fig. 1; Fig. 3, is an enlarged sectional view on the line 3—3, Fig. 1; Fig. 4, is an enlarged sectional view on the line 4—4, Fig. 1; Fig. 5, is a sectional perspective view of part of the turbine wheel; Fig. 6, is a detached sectional view illustrating a detail of the invention, and Figs. 7, 8 and 9, are detailed perspective views of parts of the apparatus.

Referring to the drawings, A is the body of a washing machine having a shaft B extending through one end.

D is a frame secured to the body of the washing machine in any suitable manner, and this frame supports the motor casing E and the bearings for the gearing between the motor and the shaft B of the machine. The casing E is made in two parts e, e bolted together as shown, and within the casing is a turbine wheel F mounted on the shaft F' adapted to bearings e' in the casing E. The shaft F' has at its inner end a pinion g, Fig. 2, which meshes with a gear wheel G on a shaft G' adapted to bearings e² and d. This gear wheel is mounted in the present instance on an elongated hub of 55 a pinion G² which meshes with a gear wheel

b secured to the shaft B. It will be understood, however, that this arrangement of gearing may be modified without departing from the essential features of my invention. The gearing will depend entirely upon the speed desired for the driven element.

The turbine wheel F is made double, as shown in Figs. 2 and 5, having two lines of pockets or blades, one facing in one direction and the other in the opposite direction. 65 These blades are formed on rings f, f' bolted or riveted to the body of the wheel as at f².

There are two nozzles C and C', one arranged at one side of the casing and the other arranged at the other side of the casing, the nozzle C projects a jet against the blades f while the nozzle C' projects a jet against the blades f', and I provide means for directing fluid under pressure to either nozzle. It will be noticed that each nozzle 75 is removable from the casing and is made as illustrated and described in an application for patent filed by me even date here-with.

I is a valve chest in which is a valve i having a stem i' which passes through a stuffing box i².

k is a fluid admission pipe communicating with one end of the valve casing, c' is a pipe leading from the same end of the valve casing to the nozzle C', and c is a pipe leading from the opposite end of the valve casing to the nozzle C.

On the end of the valve rod i² is a head i³ adapted to guidways i⁴ in an extension of 90 the valve chest, and mounted between the head and the body of the chest is a coiled spring I' tending to keep the head projected and the valve in its forward position, which will close the passage leading to the pipe c' 95 and open the passage leading to the pipe c.

Mounted in a bearing on the casing E is a shaft M on which is mounted a hub m having four arms m' in the present instance. On the gear wheel b is a pin b' which projects so as to contact with the arms m', moving the hub m a quarter turn at each revolution of the gear wheel b. Loose on the opposite end of the shaft M is a cam N which actuates the head i³ and shifts the valve to 105 the position shown in Fig. 1. When the cam is clear of this head the spring returns the valve to its forward position. Keyed to the shaft is an arm n which is engaged by a pin n' on the cam N as shown in Figs. 6, 8 and 9, 110

and this arm moves intermittently with the hub m . A spring m on the shaft tends to keep the hub m in frictional contact with the bar of the shaft so that it will not move past the position in which the pin b' leaves it, thus insuring the proper movement of the parts. In the present instance the cam N will be moved after the wheel b has completed four revolutions. This movement of the cam will reverse the valve so as to reverse the direction of movement of the wheel b . Then it will make four revolutions in the opposite direction. Thus the driving shaft is automatically reversed at every fourth revolution.

I claim:

1. The combination of a turbine motor, an inclosing casing a wheel therein, two sets of blades on the periphery of said wheel, 20 one set facing in one direction and the other facing in the opposite direction, two nozzles, one in line with one set of blades and the other in line with the other set of blades, a valve capable of directing the flow of fluid 25 to either one of said nozzles, and means for actuating the said valve, the same including a spring tending to hold it in one position, and a periodically operated cam for moving it to another position against the action of 30 said spring.

2. The combination of a turbine motor, an inclosing casing, a wheel therein, two sets of blades on the periphery of said wheel, one set facing in one direction and the other facing 35 in the opposite direction, two nozzles, one in line with one set of blades, and other in line with the other set of blades, a valve controlling the flow of fluid to either nozzle, and automatic mechanism for shifting the 40 valve so that the wheel is first driven in one direction and then in the opposite direction, said mechanism including a device tending to retain said valve in one of its two positions, and means for periodically moving it 45 against such device to its other position.

3. The combination in a fluid motor of a casing, a shaft, a wheel having two sets of blades thereon, one set facing in one direction and the other facing in the opposite direction, two nozzles, one in line with one set 50 of blades and the other in line with the other set of blades, a valve capable of directing motive fluid to either of said nozzles, a shaft, a hub on the shaft provided with arms, a wheel having a pin thereon engaging the 55 armed hub, a spring for moving the valve in one direction, and a cam controlled by the

hub for moving the valve in the opposite direction.

4. The combination in a motor of a casing, 60 a wheel mounted therein, having two sets of blades, one facing in one direction and the other facing in the other direction, two nozzles, one in line with one set of blades, and the other in line with the other set of blades, 65 a valve chest communicating with both nozzles, a valve therein, a shaft, a cam loose on the shaft, an armed hub fast to the shaft, an arm also fast to the shaft and arranged to engage the cam, a driven wheel having a pin 70 thereon arranged to engage the arms of the hub so as to automatically shift the valve to reverse the motor.

5. The combination in a motor of a casing, 75 a wheel mounted therein having two sets of blades, one facing in one direction and the other facing in the opposite direction, two nozzles facing in opposite directions and one in line with one set of blades and the other in line with the other set of blades, a valve 80 for controlling the flow of fluid to the nozzles, a shaft, a hub thereon having arms, a pin on a driven element arranged to strike the arms and turn the hub and shaft, a cam loose on said shaft and arranged to actuate 85 the valve, a pin on the cam and an arm keyed to the shaft for moving the cam.

6. The combination in a turbine motor of a shaft, two sets of vanes on said shaft, one set facing in one direction and the other set facing in the opposite direction, a casing 90 inclosing the vanes, two nozzles, one on one side of the casing and in line with one set of vanes and facing in one direction, the other on the other side of the casing and in line 95 with the other set of vanes and facing in the opposite direction; a valve casing common to the two nozzles, a pipe connecting one end of the casing with one nozzle, and a pipe connecting the other end of the casing 100 with the other nozzle, a fluid supply pipe connected with one end of the casing, a valve in the casing, a valve rod, a head on the valve rod, a spring tending to force the head and valve forward and means actuated by a 105 driven element for shifting the valve at intervals.

In testimony whereof, I have signed my name to this specification, in the presence of two subscribing witnesses.

THOMAS SUMNER PATTERSON.
